CARTON FEEDING MECHANISM

Lawrence G. Bateman, Toronto, Ontario, Canada, assignor to Delamere & Williams Company, Limited, West Toronto, Ontario, Canada, a corporation of Ontario

Application November 16, 1951, Serial No. 256,800

6 Claims. (Cl. 271—31)

This invention relates to carton-feeding mechanism. One object of the invention is to provide a novel and improved carton-feeding mechanism for feeding cartons from a stack in succession, opening the same and delivering them into pockets of a conveyer by which the open cartons may be presented to instrumentalities for performing further operations thereon, such as for folding and sealing the bottom flaps of the cartons.

A further object of the invention is to provide novel carton-feeding mechanism of the character specified wherein provision is made for advancing the stack of cartons in variable increments proportional to the thickness of one or more of the cartons being withdrawn from the stack, to the end that a substantially uniform pressure may be maintained on the stack of cartons being fed.

With these general objects in view, and such others as may hereinafter appear, the invention consists in the carton-feeding apparatus and in the various structures, arrangements and combinations of parts hereinafter described and particularly defined in the claims at the end of this specification.

In the drawings illustrating the preferred embodiment of the invention, Figs. 1 and 1a represent a plan view of the present carton feeder; Fig. 2 is a side elevation of the same; Figs. 3 and 4 are plan-view details, partly in cross section, of the carton-withdrawing and opening mechanism in different positions of operation; Fig. 5 is a cross-sectional detail view of a portion of the driving mechanism as taken on the line 5—5 of Fig. 2; Fig. 6 is a front-elevation-detail view, partly in cross section, of the stack-advancing mechanism; Fig. 7 is a cross-sectional view taken on the line 7—7 of Fig. 6; Fig. 8 is a cross-sectional detail view taken on the line 8—8 of Fig. 6; Fig. 9 is a detail view in side elevation of a portion of the mechanism shown in Fig. 6; Fig. 10 is an enlarged detail view, partly in cross section, of valve mechanism forming a part of the carton-withdrawing device; and Fig. 11 is a cross-sectional view taken on the line 11—11 of Fig. 10.

In general, the present invention contemplates carton-feeding apparatus in which provision is made for feeding a stack of collapsed cartons into operative relation to a carton-withdrawing and opening means arranged to transfer successive foremost cartons in the stack in their open condition into successive pockets of a conveyer which may form part of a packaging machine adapted to close the bottom flaps of the cartons.

An important feature of the present invention resides in the provision of stack-advancing means for moving the stack forwardly in order to compensate for the carton blanks withdrawn from the stack and to present successive foremost cartons in the stack into operative relation to the withdrawing means. Prior to the present invention, the carton-stack advancing or compensating movement has been attempted by pawl and ratchet mechanism controlled by withdrawal of cartons from the stack, thus limiting the advancing movement to definite increments as effected by one or more teeth of the ratchet without any definite correlation between the distance thus advanced and the exact advance required by the withdrawal of one or more carton blanks. The carton stack is usually supported in a magazine, and one disadvantage resulting from the prior advancing mechanism was the possibility of an overthrow or overfeeding of the stack against the retaining elements at the forward end of the magazine so that the cartons became tightly jammed therein, thus

2

preventing easy removal or free withdrawal of the foremost carton by the withdrawing device.

In accordance with the present invention, provision is made for advancing the stack in variable increments in accordance with and directly proportional to the thickness of one or more of the cartons withdrawn, whereby to maintain the forward end of the stack under a predetermined and substantially uniform pressure against the retaining elements at the forward end of the magazine and in operative relation to the withdrawing device so as to permit free withdrawal of successive foremost carton blanks from the magazine at all times.

Referring now to the drawings, in general, 10 represents a magazine arranged to support a stack of knocked down or collapsed cartons 12 in a position to present the foremost carton in the stack in operative relation to a carton-withdrawing and opening device, indicated generally at 14. The latter is arranged to withdraw and open successive collapsed cartons from the magazine and to transfer the cartons in their open condition into successive pockets 16 defined by spaced blocks 18 attached to an endless conveyer belt 20. The conveyer belt 20 is preferably arranged to travel in a horizontal plane around a pair of spaced pulleys, one of which is indicated generally at 22, and the conveyer 20 may form part of a packaging machine of the type illustrated and described in the United States Patent No. 1,527,030 to R. D. Delamere et al., which is adapted to close and seal the bottom flaps of the carton preparatory to the filling thereof.

The carton blanks 12 may be of a well known type having a tubular body portion divided by score lines into a four-walled structure and having top and bottom closing flaps. As herein shown, the carton blanks are supported vertically with their lower edges resting upon chains 24, 26, the stack being supported laterally between guide rails 28, 30. The forward end of the stack is supported in the magazine by vertical retaining strips 32, 34 engaging the marginal side edges of the stack, and by depending bars 36 supported above the stack and engageable with the upper marginal edge thereof, as shown. Provision is made for advancing the stack along the magazine and for urging the forward end of the stack against the marginal retaining members as the cartons are withdrawn from the magazine during the operation of the machine, as will be hereinafter described.

Referring now to Figs. 1 and 2, the carton-withdrawing and opening device 14 may comprise a plurality of transfer arms 40 provided with suction cups 44, and the arms are mounted fast on a vertical rocker shaft 42. The transfer arms 40 are arranged to be rocked clockwise viewing Fig. 1 to present the suction cups 44 into engagement with the foremost carton in the stack, as shown in Fig. 1, and are then rocked counterclockwise to withdraw the carton from the stack. The suction cups 44 are arranged to engage a narrow end wall 45 of the carton, and as the carton is rocked outwardly, the outer corner of the carton adjacent the opposing narrow end wall engages the face of the conveyer belt 20. The suction is then cut off, releasing the carton from the suction cups 44, and the slide 46 then pushes the end of the carton adjacent the end wall 45 into the position shown in Fig. 4. During this operation the carton moves from the position shown in Fig. 3 to that shown in Fig. 4, and the corner of the carton illustrated as engaging the conveyer belt 20 slides upon the belt as the latter moves until the adjacent end wall is engaged by the oncoming block 18. The slide 46 moves the carton into a position where the leading end thereof enters the space between the conveyer belt 20 and the guide rail 48 so that the continued movement of the block 18 advances the carton in its fully open position between the conveyer belt and the guide rail 48 as shown in Fig. 4. It will be understood that the conveyer belt 20 is operated continuously at a relatively high speed, and in the continued movement of the conveyer, the opened cartons are retained in their pockets 16 by the outer guide rail 48 arranged concentrically with the conveyer belt 20. The lower end of the carton may be supported by a bottom plate 50 during the transfer operation, and a bottom rail 52 may support the lower end of the carton in the pocket 16, as shown in Fig. 4.

As illustrated in Figs. 1 and 2, the vertical rocker shaft 42 is rotatably supported in upper and lower bearing members 41, 43 respectively, and the mechanism for rocking the vertical shaft 42 to effect withdrawal and transfer of successive carton blanks from the magazine 10 to the pockets 16 in their open condition may comprise a gear and rack mechanism operated by an eccentric. As herein shown, the lower end of the shaft 42 is reduced in diameter and provided with a segmental gear 54 fast thereon, as illustrated in Fig. 5. A rack 56 in meshing engagement with the segmental gear is supported for reciprocation between gibs 58, 59 attached to a side frame 60 of the apparatus. The rack is pivotally connected by a pin 62 to a link or strap 64 cooperating with an eccentric disk 66 fast on a continuously rotated drive shaft 68. The drive shaft may be rotated from and in timed relation to the packaging machine through connections including a chain and sprocket drive, indicated generally at 70.

Suction is supplied to the transfer arms 40 through the rocker shaft 42 which is provided with an axial bore 72 communicating with the suction cups 44 through passageways 74, 76 formed in the arms 40, as shown in Figs. 3 and 4. Provision is made for controlling the suction to effect release of a carton at a predetermined time in the withdrawing and opening cycle to permit the carton to be pushed into a pocket 16 by the reciprocal slide member 46. As shown in Figs. 10 and 11, a reduced-diameter portion at the lower end of the shaft 42 is provided with a ball bearing 78 and extends beyond the ball bearing into a closed chamber 80 formed in the bearing bracket 43 attached to the side frame 60. The chamber 80 communicates with the axial bore at the lower end of the shaft 42 and is connected by a diagonal passageway 82 with the lower end of a port 84. The upper end of the port 84 communicates with a chamber 86 formed in a slide-valve member 88. A second port 90 in communication with the valve chamber 86 comprises the suction inlet which may be connected by a pipe 92 to any usual or preferred source of vacuum.

The slide-valve member 88 is supported for sliding movement to effect communication with the port 84 when the member is moved to the left viewing Fig. 10, and to open the port 84 to the atmosphere when the valve member is moved to the right, and as herein shown, the valve member 88 is provided with a longitudinal slot 94 in its upper face arranged to receive the lower edge of a bar 96 secured to the rack member 56 by screws 98. In order to slide the valve member relative to the port 84, the bar 96 is provided with valve-engaging fingers 100, 102 adjustably secured at each end of the bar by bolts 104 arranged to extend through slots 106 formed in the bar. In operation, when the rack 56 is extended or moved to the left viewing Fig. 11, the suction arms 40 are rocked into engagement with the foremost carton in the stack, and during such movement the valve member 88 is engaged by the finger 102 and shifted to the left into position to communicate with the port 84, as illustrated in Fig. 10. During the retracting stroke of the rack, the suction arms 40 are rocked outwardly to withdraw the foremost carton in the stack, and when the rack has moved a distance such as to rock the suction arms through approximately 90°, as illustrated in Fig. 3, the finger 100 engages the valve member 88 to push it to the right a distance such as to uncover the port 84 and open the same to the atmosphere, thus releasing the carton from the suction cups 44 while the suction arms continue to rock beyond the 90° point. The port 84 will remain open to the atmosphere until the cycle is repeated and the finger 102 engages the valve member to again shift it to the left into communication with the suction port 84.

As illustrated in Fig. 3, when the transfer arms 40 are rocked through 90° during the withdrawing stroke, the narrow end wall 45 of the carton held by the suction cups 44 engages guide brackets 108. When the carton is pushed by the reciprocal pusher member 46 after the suction is discontinued to release the carton from the suction cups, the carton is guided by the bracket 108 into the space between the rail 48 and the conveyor 20. The guide brackets 108 may comprise U-shaped plates, as viewed in Fig. 2, which are attached to the front face of the side frame 60.

The reciprocal pusher member 46 is provided with three elongated fingers 47, see Fig. 2, arranged to straddle the suction arms 40, and the body portion of the 85

pusher may be adjustably secured to a slide member 110 by bolts 112 extended through slots 114 formed in the slide member. As herein shown, the slide member 110 is mounted to slide between gibs 116 attached to the side frame 60, and is arranged to be reciprocated in timed relation to the carton-withdrawing movement through connections including a bell crank pivotally mounted at 118. One arm 120 of the bell crank is connected by a link 122 to the slide member 110 and the other arm 124 is connected by a link 126 to a crank pin 128 secured to and movable with the eccentric disk 66. In operation, the reciprocal pusher member 46 starts its forward movement at substantially the same time as the rack 56 starts its retracting movement to effect withdrawal of a carton from the magazine, but the forward end of the pusher member 46 does not reach a position to engage the carton until the suction arms 40 are rocked outwardly substantially 90° whereupon continued movement of the pusher member 46 urges the carton along the guide members 108 and into the pocket 16 as described. It will be understood that the withdrawing and transferring operation described is continuous and may be performed at a relatively high speed in the neighborhood of 240 cartons a minute.

25 As illustrated in Figs. 1 and 2, the magazine 10 includes an elongated supporting bracket 130 over which the upper runs of the chains 24, 26 travel, being guided upon tracks 25, 27 respectively, attached to the upper face of the bracket 130. The guide rails 28 engaging one side of the stack are secured to the side frame 60, and rails 29 coextensive with the rails 28 may be supported at one end by brackets 31 attached to the side frame 60 and at their other ends by a bracket 33 attached to the supporting bracket 130. The opposing guide rails 30 may be adjustably supported on rods 132 carried by brackets 134 attached to the supporting bracket 130.

35 Provision is made for advancing the stack 12 in the magazine in variable increments in accordance with and directly proportional to the thickness of one or more successive carton blanks withdrawn from the magazine, and as herein shown, the stack-supporting chains 24, 26 are arranged to run over driven sprockets 136, 138 fast on a shaft 140 rotatably supported in bearings 142, 144 attached to the supporting bracket 130 at one end thereof. At the other end of the bracket, the chains are arranged to run over idler sprockets 146, 148 loosely mounted on a shaft 150 supported in slots 152 formed in side bars 154, 156 attached to and extended rearwardly from the back end of the bracket 130, as shown in Fig. 50 1a. The shaft 150 is adjustably positioned in the slots by chain-tightener rods 158 secured to collars 160 fast on the shaft 150 and extended through an end plate 162 secured to the ends of the bars 154, 156. The rods 158 are provided with lock nuts 164 for adjusting the position of the shaft 150 to effect tightening of the chains.

55 As shown in Figs. 1 and 2, a backing member 166 engaging the rear end of the stack 12 and detachably secured to the chains 24, 26 is arranged to urge the stack forwardly in the magazine against the marginal retaining members 32, 34 and 36 at the front end thereof and to effect advancement of the stack when the chains 24, 26 are moved. The backing member 166 is detachably secured to the chains by pins 168 carried by the backing member and engageable with openings in the chains.

70 The pins 168 are attached to a hand lever 170 pivotally mounted in the backing member whereby to permit withdrawal of the pins and adjustment of the backing member to a different position when additional carton blanks are supplied to the magazine, as clearly shown in Fig. 2.

75 Referring now to Figs. 6 and 7, an extended portion of the sprocket shaft 140 is provided with a roller clutch mechanism, indicated generally at 172, and which includes a circular disk 174 fast on the shaft 140, and comprising the driven member of the clutch; a rock lever 173 comprising the driving member of the clutch and including spaced arms 175, 176 pivotally mounted about the shaft 140. The lever 173 is provided with a friction plate 178 at its upper end. A cylindrical roller 180 mounted to be capable of wedging action between the periphery of the disk 174 and the underside of the friction plate 178 to couple the driving and driven elements together when permitted to do so. As shown in Fig. 7, the spaced arms 175, 176 of the rock lever 173 are mounted to rock on ball bearings 182 carried by laterally extended hub portions of the disk 174 and are connected at their lower

ends by bolts 184 to an extension 186. As illustrated in detail in Fig. 8, the cylindrical roller 180 is mounted between the arms of a U-shaped retaining member 190 and is resiliently urged into wedging position by a pair of springs 192 connecting the arms of the U to the rock lever. The transverse leg 193 of the U may be V shaped in cross section to embrace the roller 180, as shown in Fig. 6. The rock lever 173 is arranged to be oscillated through connections to the extension 186 including a link 194 connecting the extension to a stud 196 carried by an arm 198 fast on an extended portion of the eccentric stud 128, as best shown in Fig. 5, thus providing in effect a relatively short crank movement relative to the main driving shaft 68 for incrementally advancing the chains 24, 26 through the operation of the roller clutch 172.

In the operation of the roller clutch 172, when the rock lever 173 is rocked in a counterclockwise direction, viewing Fig. 6, the roller 180, held in wedging position by the springs 192, will effect rotation of the disk 174 as a unit with the rock lever to advance the stack, and conversely, when the rock lever 173 is rocked in a clockwise direction, the roller 180 will merely roll with relation to the disk 174 without effecting any rotation thereof. A second roller 200 is held in a stationary retainer 202 for cooperation with the periphery of the disk 174 and is arranged to prevent reverse movement of the disk, as clearly shown in Fig. 6. The retainer 202 may be secured to a bracket 204 attached to the side frame member 60.

In practice, the stack of cartons is preferably held under a slight compression so as to effect a substantially uniform pressure against the forward end of the magazine, such as to maintain the stack in a relatively loose condition whereby to permit easy withdrawal of successive foremost cartons. Provision is made for controlling the roller clutch to effect advancement of the stack in variable increments so as to maintain such uniform pressure and to prevent overcrowding or overfeeding of the stack in the magazine to an extent such as to interfere with easy withdrawal of successive cartons by the suction-withdrawing device.

As herein shown, the control mechanism may include a feeler finger 206 pivotally mounted at 208 and arranged to engage the front end of the stack, the finger being connected by a link 210 to one arm 212 of a two-armed lever pivotally mounted at 214. The second arm 216 is connected by a spring 218 to a stud 220 fixed in the side frame 60 so as to resiliently urge the feeler finger against the front end of the stack. The second arm 216 of the lever is also connected by a link 222 to a roller-disengaging member 224 slidably mounted between the disk 174 and the plate 178. In operation, the disengaging member 224 is arranged to engage the roller 180 to hold it out of wedging position between the disk 174 and the plate 178 when the feeler finger 206 is in substantially parallel engagement with the front end of the stack, as shown in Figs. 3 and 4, and when one or more carton blanks are withdrawn from the magazine so as to permit rocking of the feeler finger 206 inwardly or in a clockwise direction, the disengaging member 224 is retracted to permit coupling engagement of the roller 180 between the disk and the plate. It will be observed that the friction plate 178 is arranged at right angles to a centerline drawn through the disk 174 and is spaced from the disk so that wedging engagement of the roller 180 occurs at a predetermined point between the disk and the plate. With this construction it will be seen that a relatively small inward rocking movement of the feeler finger 206 will retract the disengaging member 224 only slightly so that during the initial portion of the full stroke of the rock lever 173 in a counterclockwise direction, the roller 180 is held out of wedging engagement, and during the latter part of the stroke of the rock lever, the roller is engaged between the disk and the plate at a point beyond the influence of the disengaging member 224 to effect an advance of the stack through a relatively small increment directly proportional to the rocking movement of the feeler finger 206.

In this manner, the stack may be advanced periodically through either a full stroke or a partial stroke in accordance with the rocking movement of the feeler finger 206 to maintain the forward end of the stack against the retaining members 32, 34 and 36 in operative relation to the withdrawing device and with a substantially uniform pressure such as to maintain the cartons in a relatively

free condition whereby to permit easy withdrawal of successive foremost cartons from the magazine.

In order to prevent interference with the feeler finger 206 and associated linkage, including the clutch-disengaging member 224, when the foremost carton is being withdrawn from the magazine, provision is made for clamping the linkage during a predetermined time in the withdrawing cycle of operation, and as herein shown, the clamping means may include a lower stationary member 226 engaging the underside of the link rod 222, and an upper movable member 228 in yielding engagement with the upper side of the rod 222 and which is arranged to cooperate with the lower clamp to yieldingly hold the entire control linkage in its clamped position during the withdrawal of a carton. The stationary clamp member 226, threaded at its lower end, may be adjustably mounted in a laterally extended bar 230 secured to an angle bracket 232 adjustably attached to the side frame 60. The movable clamp member 228 is slidably mounted in an L-shaped member 234 attached to and movable with a vertical rod 236 which may extend through an opening in the bar 130. A compression spring 238 coiled about the stem of the upper clamp member 228 and interposed between the head of the clamp and a portion of L-shaped bracket is arranged to yieldingly urge the upper clamp into engagement with the upper side of the rod 222. The vertical rod 236 is connected at its lower end to an intermediate portion of a lever 240 pivotally mounted at 242, and a link 244 connects the lever 240 to the arm 124 forming a part of the pusher-actuating linkage for reciprocating the pusher member 46, as above described.

In operation, the yieldingly pressed upper clamp member 228 may be maintained in an elevated or non-clamping position by the linkage described during a major portion of a cycle of operation, and when so maintained cooperates with the lower clamp member to form a guide to slidably support the rod 222, and during the withdrawing portion of the cycle, the upper clamp member is caused to descend through the described linkage to firmly engage the rod 222 and hold it in its clamped position, thus rendering the control mechanism inoperative until a carton is withdrawn from the magazine. Thereafter, the upper clamp member 228 is again elevated to permit the feeler finger 206 to rock against the forward end of the stack and effect adjustment of the disengaging member 224 to control the amount of advance of the stack along the magazine when the rocker arm 173 is operated.

From the above description it will be seen that the present carton-feeding apparatus is arranged to periodically advance the stack of collapsed cartons in infinitesimally variable increments within minimum and maximum limits in accordance with and directly proportional to the depletion of cartons from the magazine so as to maintain the forward end of the stack in operative relation to the withdrawing mechanism and to maintain a substantially uniform pressure of the stack against the retaining elements such as to permit easy withdrawal of successive foremost cartons in the magazine. It will also be seen that the present variable-increment stack-advancing mechanism is adapted to feed carton blanks of different thicknesses and to effect advancement of the stack to compensate for variable thicknesses without the necessity of making any adjustment or interchange of operating parts.

While the preferred embodiment of the invention has been herein illustrated and described, it will be understood that the invention may be embodied in other forms within the scope of the following claims.

Having thus described the invention, what is claimed is:

1. Carton-feeding apparatus having, in combination, means for supporting a stack of cartons, means for withdrawing successive foremost cartons from the stack, means for periodically advancing the stack to move successive foremost cartons into operative relation to the carton-withdrawing means, and control means including means engageable with the carton being withdrawn and responsive to the withdrawal of cartons from the stack and operatively connected to said advancing means for varying the advancing movement in accordance with and directly proportional to the thickness of the individual cartons withdrawn from the stack, said advancing means including a roller clutch, and means for oscillating said clutch through a fixed stroke, said control means further includ-

ing a disengaging member movable into different positions relative to the stroke of said roller clutch for varying the effective advancing stroke.

2. Carton-feeding apparatus having, in combination, means for supporting a stack of cartons, means for withdrawing successive foremost cartons from the stack, means for periodically advancing the stack to move successive foremost cartons into operative relation to the carton-withdrawing means, and control means including means engageable with the carton being withdrawn and responsive to the withdrawal of cartons from the stack and operatively connected to said advancing means for varying the advancing movement in accordance with and directly proportional to the thickness of the individual cartons withdrawn from the stack, said advancing means including a roller clutch, and means for oscillating said clutch through a fixed stroke, said control means further including a disengaging member movable into different positions relative to the stroke of said roller clutch for varying the effective advancing stroke, and means for clamping said control means to prevent interference with and movement of said disengaging member during the withdrawal of a carton from the stack.

3. Carton-feeding apparatus having, in combination, a magazine for supporting a stack of cartons, retaining elements cooperating with opposed marginal portions of the front of the stack, a movable backing member engageable with the other end of the stack, suction means for withdrawing successive foremost cartons from the stack and out of said retaining elements, means operatively connected to said backing member for periodically advancing the stack against said retaining elements to move successive foremost cartons into operative relation to the carton-withdrawing means, said advancing means including a roller clutch, means for oscillating the clutch through a fixed stroke, control means including a feeler finger movable into engagement with successive foremost cartons in the stack, and a roller disengaging member operatively connected to and movable with said feeler finger, said disengaging member being movable into different positions relative to said stroke to vary the effective advancing stroke through different increments directly proportional to the movement of said finger in response to the withdrawal of cartons from the stack whereby to prevent overcrowding of the cartons against the retaining elements and to permit easy withdrawal of successive foremost cartons from the stack.

4. Carton-feeding apparatus having, in combination, a magazine for supporting a stack of cartons, retaining elements cooperating with opposed marginal portions of the front of the stack, a movable backing member engageable with the other end of the stack, suction means for withdrawing successive foremost cartons from the stack and out of said retaining elements, means operatively connected to said backing member for periodically advancing the stack against said retaining elements to move successive foremost cartons into operative relation to the carton-withdrawing means, said advancing means including a roller clutch, means for oscillating the clutch through a fixed stroke, control means including a feeler finger movable into engagement with successive foremost cartons in the stack, and a roller disengaging member operatively connected to and movable with said feeler finger, said disengaging member being

movable into different positions relative to said stroke to vary the effective advancing stroke through different increments directly proportional to the movement of said finger in response to the withdrawal of cartons from the stack whereby to prevent overcrowding of the cartons against the retaining elements and to permit easy withdrawal of successive foremost cartons from the stack, and means for locking said control means to prevent movement of said feeler finger and said disengaging member during the withdrawal of a carton from the stack.

5. In apparatus of the character described, in combination, means for supporting a stack of articles to be fed, means for withdrawing successive foremost articles from the stack, and means for incrementally advancing the stack to move successive foremost articles into operative relation to the withdrawing means, said advancing means including a roller clutch having a driving member, a driven member and a roller coupling member, means for oscillating said driving member through a fixed stroke each cycle of operation, and control means including a pivoted finger yieldingly engageable with successive foremost articles in the stack, and a clutch-disengaging member connected to said finger and to said roller, said disengaging member being movable to engage said roller at different positions relative to said fixed stroke to variably limit the effective advancing stroke through different increments directly proportional to the movement of said feeler finger in response to withdrawal of an article from the stack.

15 6. In apparatus of the character described, in combination, means for supporting a stack of articles to be fed, means for withdrawing successive foremost articles from the stack, and means for incrementally advancing the stack to move successive foremost articles into operative relation to the withdrawing means, said advancing means including a roller clutch having a driving member, a driven member and a roller coupling member, means for oscillating said driving member through a fixed stroke each cycle of operation, and control means including a pivoted finger yieldingly engageable with successive foremost articles in the stack, and a clutch-disengaging member connected to said finger and to said roller, said disengaging member being movable to engage said roller at different positions relative to said fixed stroke to variably limit the effective advancing stroke through different increments directly proportional to the movement of said feeler finger in response to withdrawal of an article from the stack.

20 7. In apparatus of the character described, in combination, means for supporting a stack of articles to be fed, means for withdrawing successive foremost articles from the stack, and means for incrementally advancing the stack to move successive foremost articles into operative relation to the withdrawing means, said advancing means including a roller clutch having a driving member, a driven member and a roller coupling member, means for oscillating said driving member through a fixed stroke each cycle of operation, and control means including a pivoted finger yieldingly engageable with successive foremost articles in the stack, and a clutch-disengaging member connected to said finger and to said roller, said disengaging member being movable to engage said roller at different positions relative to said fixed stroke to variably limit the effective advancing stroke through different increments directly proportional to the movement of said feeler finger in response to withdrawal of an article from the stack, and means for clamping said control means to prevent interference with said feeler finger and said disengaging member during the withdrawal of an article from the stack.
